ware

No Drawing. Application September 15, 1942,
Serial No. 453,454

21 Claims. (Cl. 252—32)

This invention relates to new and useful compositions and it involves a lubricating composition comprising a polar substituted metal alkyl carboxylate and an ester of an hydroxy substituted aliphatic carboxylic acid.

In the improvement of mineral lubricating oils, especially for use in internal combustion engines, it has been the object of long sustained research to produce an oil which does not deteriorate rapidly and which does not harmfully affect the engine; for example, an oil which does not cause fouling of pistons, sticking of piston rings and corrosion of susceptible alloy bearings, such as copper-lead and cadmium-silver bearings. Stability toward oxygen is also a desirable attribute of lubricants in general and of cable, switch and transformer oils and the like.

In the history of development of stable lubricants for internal combustion engines, it was found relatively early that certain types of oil are less susceptible to oxidation than others. Thus it was found that paraffinic oils are more stable than naphthenic oils, at least as regards atmospheric oxidation. Paraffinic oils were, therefore, at a premium and the effort was made to refine non-paraffinic oils to produce paraffinic oils. However, with the advent of Diesel and other engines operating at temperatures of 400° to 650° F. under pressures of oxidizing combustion gases of 750 to 1200 pounds per square inch, it was found that, in some respects at least, naphthenic oils are superior; for example, they were found to cause less fouling of the pistons and sticking of piston rings.

A marked advance was made in the improvement of mineral oils with respect to maintenance of engine cleanliness and prevention of piston ring sticking, when metal naphthenates, metal phenates and metal salts of fatty acids were advanced as lubricant additives. Small amounts of these additives were found greatly to improve mineral lubricating oils with respect to engine cleanliness and piston ring sticking. However, the advent of harder but more easily corrodible alloy bearings such as copper-lead and cadmium-silver bearings, and a substantial increase in operating temperature, gas pressure and loads of engines made a greater demand upon mineral oil lubricants, a demand not entirely satisfied by the then known compounded lubricants.

In various of our copending applications there are disclosed improvements upon the use of metal naphthenates, metal phenates and metal salts of fatty acids in lubricating oils, such improvements relating to the use in oils of various polar substituted metal alkyl carboxylates. As set forth in said applications, improvement results from the presence of a polar group in the molecule of a metal alkyl carboxylate in close proximity to a metal alkyl carboxylate group. (By "alkyl carboxylic acid" is meant an acid having a COOH group attached to an aliphatic carbon atom, and by "metal alkyl carboxylate" is meant a metal salt of such an acid; that is, a compound having in its molecule the group

20 in which M is a monovalent metal or the hydrogen equivalent of a polyvalent metal, and the carbon atom shown with free valencies is an aliphatic carbon atom, said valencies being satisfied by carbon, hydrogen or other atoms or groups of atoms. This group —COOM is referred to herein 25 as a "metal alkyl carboxylate group.")

More specifically, in our copending application Serial No. 322,946, filed March 8, 1940, of which the present application is a continuation-in-part, it is disclosed that metal salts of aliphatic polycarboxylic acids are highly efficient additives 30 for lubricating oils, being, among other things, effective in inhibiting piston ring sticking and promoting engine cleanliness without the highly 35 corrosive action toward copper-lead and cadmium-silver alloy bearings of unsubstituted metal salts of fatty acids, and that the action of these salts is further improved by the presence therein of certain polar substituents in positions close to 40 a metal alkyl carboxylate group, preferably in the alpha, beta or gamma position with respect to said group. There is disclosed in said copending application a large number of effective polar substituents.

45 In two other of our copending applications we have set forth the extension of this discovery to other and particular polar substituted metal alkyl carboxylates. These further applications, of which the present application is also a continuation-in-part, are as follows: Serial No. 350,054,

filed August 2, 1940, now Patent No. 2,308,502, issued January 19, 1943, Certain oxygen substituted metal alkyl carboxylates; Serial No. 350,055, filed August 2, 1940, now Patent No. 2,308,503, issued January 19, 1943, Certain sulfur, selenium or tellurium substituted metal alkyl carboxylates.

The polar substituents disclosed in said copending applications, as well as other polar substituents (that is, substituents which are electro-negative or electro-positive in character and impart to an otherwise non-polar molecule, such as benzene or methane, a dipole moment) possess, as we have discovered, the property of improving metal alkyl carboxylates as lubricant additives; in particular, the property of detergency in an internal combustion engine unaccompanied by, or accompanied by relatively little corrosiveness toward susceptible alloy bearings.

We have now found, however, that polar substituted metal alkyl carboxylates can be greatly improved as hydrocarbon oil additives and as constituents of lubricants if they are employed in conjunction with esters of hydroxy substituted aliphatic carboxylic acids.

In a preferred embodiment of the invention, a polar substituted metal alkyl carboxylate and an ester of an hydroxy substituted aliphatic carboxylic acid are employed in relatively small amounts, dispersed in a hydrocarbon or mineral oil of lubricating viscosity.

Another embodiment of the invention includes the use of larger quantities of the said metal alkyl carboxylate and the said hydroxy ester, even to the exclusion of hydrocarbon oil. Thus a grease may be formed in which the polar substituted metal alkyl carboxylate constitutes all or a large part of the soap ingredient, the hydroxy ester constitutes all or a large part of the oily ingredient, and hydrocarbon oil may be present in greater or lesser quantity or may be entirely absent, as desired.

Still another embodiment of the invention comprises the use of a viscous liquid hydroxy ester, such as amyl citrate, as the effective lubricant, to which is added a relatively small amount of a polar substituted metal alkyl carboxylate as an improvement agent.

A further embodiment of the invention comprises the use of relatively small quantities of a polar substituted metal alkyl carboxylate and of an ester of an hydroxy substituted aliphatic carboxylic acid in a non-hydrocarbon lubricant such as butyl phthalate.

In all of these and other embodiments of the invention there is present in the composition a polar substituted metal alkyl carboxylate, which may be represented as follows:

I (X)A-COOM

and an ester of an hydroxy substituted aliphatic carboxylic acid, which may be represented as follows:

II (HO)BCOOR

In both of these formulae there may be a plurality of any one or more of the groups X, COOM, COOR and OH.

In Formula I, M represents a monovalent metal or the hydrogen equivalent of a polyvalent metal, A represents an organic grouping containing an aliphatic carbon atom attached to the group COOM, and X represents a polar group which is attached to an aliphatic carbon atom close to the group COOM and preferably in the alpha,

beta or gamma position with respect to said group.

In Formula II, R represents a hydrocarbon or substituted hydrocarbon group, B represents an organic grouping containing an aliphatic carbon atom attached to the group COOR, and the OH group is attached to an aliphatic carbon atom of the group B, preferably in a position close to the group COOR, as in the alpha, beta or gamma position with respect to said group COOR.

With further reference to Formula I, the metal M may be any of a number of metals, such as sodium or potassium, but preferably it is a polyvalent metal such as an alkaline earth metal (magnesium, calcium, strontium and barium), aluminum, chromium, cobalt, nickel, lead, manganese, tin or zinc. Preferably a metal is used whose salts tend to be oil soluble and which does not promote oxidation of the oil or increase wear of relatively moving surfaces. The preferred polyvalent metals are the alkaline earth metals and zinc.

Numerous examples are given in application Serial No. 322,946 of the polar group X which is present in the molecule (X)ACOOM. The ethylenic and acetylenic groups are considered as polar groups effective in reducing corrosiveness if present in a position close to the group COOM, whether present in the same carbon chain as the COOM or in a side chain. Substituents X are preferred which are not readily hydrolyzable and do not split off readily to produce corrosive acids. Thus the nitrate ($-\text{O}-\text{NO}_2$), sulfate ($\text{O}-\text{SO}_3\text{H}$), and halogen (F, Cl, Br, I) groups are not preferred, although they may be used, because they tend to hydrolyze and form corrosive acids. Also, substituents which are thermally stable, that is, which do not break down readily at normal or moderately elevated temperatures, are preferred, although in some instances a complex polar substituent will break down into a simpler polar substituent which is effective in modifying and improving the metal alkyl carboxylate.

Following are examples of polar groups that may be employed:

$-\text{COOH}$	Carboxyl
$-\text{C}\text{SOH}$	Thionocarboxyl
$-\text{COSH}$	Thiocarboxyl
$-\text{CSSH}$	Dithiocarboxyl
Carboxyl, thionocarboxyl, thiocarboxyl and dithiocarboxyl derivatives, in which the acid hydrogen is replaced by a metal or an organic grouping (e. g. alkyl, aryl, cycloalkyl, aralkyl)	
$-\text{OH}$	Hydroxyl
$-\text{OM}$	Metallo-oxyl
$-\text{OR}_1$	Organic-substituted hydroxyl (alkoxyl, aroxyl, cycloalkoxyl, etc.)
$-\text{SH}$	Mercapto
$-\text{SM}$	Metallo-mercapto
$-\text{SR}_1$	Thio (alkylthio, arylthio, cycloalkylthio, etc.)
$-\text{S}_n\text{R}_1$	Polythio (alkylpolythio, arylpolythio, cycloalkylpolythio, etc.)
Selenium and tellurium analogues of the above mercapto, thio and polythio groups.	
$-\text{NR}_1\text{R}_2$	Amino
$-\text{NR}_1$	Imino
$-\text{NO}$	Nitroso
$-\text{NO}_2$	Nitro
$-\text{CN}$	Cyano
$-\text{NC}$	Isocyano
$-\text{NOR}_1$	Oximino
$-\text{NOR}_1\text{OR}_2$	Hydroxamino
$-\text{O}-\text{NO}_2$	Nitroato
$-\text{OCN}$	Cyanato
$-\text{NCO}$	Isocyanato
$-\text{SCN}$	Thiocyanato
$-\text{NCS}$	Isothiocyanato
$-\text{NR}_1\text{SO}_2\text{R}_3$	Isothiocyanato
$-\text{SO}_2\text{NR}_1\text{R}_2$	Sulfamino
$-\text{PR}_1\text{R}_2$	Sulfamyl
$=\text{PR}_1$	Phosphino
$-\text{PO}$	Phosphylene
$-\text{PO}_2$	Phosphoroso
$\text{O}-\text{R}_2$	Phospho
$\text{O}-\text{PO}$	Phosphato
$\text{O}-\text{R}_4$	

$O-R_1$	Phosphito
$O-R_4$	
$O-R_3$	Phosphonato
$-PO$	
$O-R_4$	
$O-R_3$	Phosphonito
$-P$	
$O-R_4$	
$O-R_4$	Phosphonito
$-PS$	
$O-R_4$	
$S-R_4$	Thiophosphonato
$-PS$	
$S-R_4$	
$=PO R_4$	Phosphinito
$=PO OR_3$	Phosphinato
$=AsR_1 R_2$	Arsino
$=AsR_1$	Arsylene
$=AsO$	Arsenos
$=AsO_2$	Arso
$=SbR_1 R_2$	Stibino
$=SbR_1$	Stibylene
$=SbO$	Stiboso
$=SbO_2$	Stibo
$=BiR_1 R_2$	Bismuthino
$=BiR_1$	Bismuthylene
$=BiO$	Bismuthoso
$=BiO_2$	Bismutho
$=SO$	Sulfonyl
$=SO_2$	Sulfonyl
$=SO_2 R_3$	Thiosulfato
$=SO_2 R_3$	Sulfano
$=SO_2 R_3$	Sulfo
$-O-SO_2 OR_2$	Sulfato
$-O-SO_2 OR_3$	Sulfito
$=SeO$	Seleninyl
$=SeO_2$	Selenonyl
$=BO$	Boryl

In the above table of polar groups, M represents a monovalent metal, such as sodium or potassium, or the hydrogen equivalent of a polyvalent metal such as magnesium, calcium, strontium, barium, zinc or aluminum; R₁ and R₂ represent the same or different groups selected from the class consisting of hydrogen and hydrocarbon or substituted hydrocarbon groups such as methyl, ethyl, butyl, cetyl, phenyl, tolyl, cetylphenyl, chlorphenyl, benzyl or naphthyl; and R₃ and R₄ represent the same or different groups selected from the class consisting of hydrogen, monovalent metals (such as sodium or potassium), the hydrogen equivalent of polyvalent metals (such as magnesium, calcium, strontium, barium, zinc or aluminum) and hydrocarbon or substituted hydrocarbon groups (such as methyl, ethyl, butyl, cetyl, phenyl, tolyl, cetylphenyl, chlorphenyl, benzyl and naphthyl). In the group S_nR₁, the subscript n is an integer greater than 1. Examples of alkyl, aryl, cycloalkyl and aralkyl groups referred to in the above table in connection with the carboxyl, thionocarboxyl, thiocarboxyl and dithiocarboxyl derivatives are the methyl, ethyl, butyl, cetyl, phenyl, cetylphenyl, tolyl, chlorphenyl, naphthyl, cyclohexyl, methylcyclohexyl, and benzyl groups. Examples of metals referred to in connection with the carboxyl, thionocarboxyl, thiocarboxyl and dithiocarboxyl derivatives are sodium, potassium, magnesium, calcium, strontium, barium, zinc and aluminum.

The group A of Formula I above may be any one of a number of groups, either purely hydrocarbon or substituted hydrocarbon. The nature of the group A and its relation to the rest of the molecule is best illustrated by the following list of metal salts of polar substituted alkyl car-

boxylic acids that may be used in accordance with the invention:

- The sodium, potassium, magnesium, calcium, strontium, barium, zinc, aluminum, chromium, cobalt, lead, nickel, manganese and tin salts (normal, basic or mixed) of alpha, beta or gamma hydroxy substituted acetic, propionic, butyric, valeric, caproic, heptanoic, caprylic, capric, lauric, myristic, palmitic, stearic, arachidic, oleic, ricinoleic, malonic, succinic, glutaric, adipic, pimelic, and suberic acids; also the salts of the same metals and the same acids substituted in the alpha, beta or gamma position by any of the following groups instead of by an hydroxy group:
- 5   carboxy, metallo-carboxy, carboxy ester, oxy-ether, thio-ether, seleno-ether, mercapto, mercaptide, amino, phosphino and cyano groups. The metal salts of naturally occurring or common hydroxy substituted carboxy acids, such as
- 10   lactic, tartaric, citric and mucic acids, constitute excellent additives without further modification, and greater oil solubility can be imparted thereto by incorporating a long chain alkyl group in the molecule, as by esterifying a carboxy group.
- 15   20   Also, excellent additives can be prepared by condensing an olefine with maleic anhydride and forming a metal alkenyl succinate, and in general metal salts of aliphatic polycarboxylic acids having two carboxy groups separated by not
- 25   30   more than three carbon atoms may be used in accordance with the invention. Metal alkyl carboxylates containing more than about 10 carbon atoms are preferred because of their greater oil solubility.
- 35   40   With further reference to Formula II above, as stated, the group R represents a hydrocarbon or substituted hydrocarbon group, the group B represents an organic grouping containing an aliphatic carbon atom attached to the group
- 45   50   COOR, and the OH group is attached to an aliphatic carbon atom of the group B, preferably in a position close to the group COOR, as in the alpha, beta or gamma position with respect thereto. Preferably the ester (HO)B(COOR) is a neutral ester of a low molecular weight (C₁ to C₆ inclusive) aliphatic alcohol and a low molecular weight (C₂ to C₆ inclusive) aliphatic mono- or polycarboxylic acid, said acid having one or more hydroxy substituents in one or more of the positions alpha, beta and gamma with respect to a carboxyl group. The group B and its relation to the rest of the molecule is best illustrated by the following list of hydroxy esters capable of use in accordance with the invention:
- 55   60   The methyl, ethyl, propyl, isopropyl, butyl, isobutyl, secondary butyl, tertiary butyl, amyl, hexyl, heptyl, octyl, nonyl, lauryl, dodecyl, tetradecyl, cetyl, and octadecyl esters of alpha, beta or gamma hydroxy acetic, propionic, butyric, valeric, caproic, enanthic, caprylic, capric, lauric, myristic, palmitic, stearic and arachidic acids, as well as the corresponding esters of glyceric, tartaric, malic, tartaric, mucic and citric acids.
- 65   70   The polar substituted metal alkyl carboxylates and the esters of hydroxy substituted aliphatic carboxylic acids may be used in widely varying amounts, depending upon the nature of the composition desired. In the preferred embodiment
- 75   80   of the invention, where said metal carboxylate and hydroxy ester are employed in relatively small amounts as additives for hydrocarbon oils of lubricating viscosity, these additives may each be employed in amounts ranging from 0.1% or lower to 10% or higher based on the finished oil,

but the metal carboxylate is preferably employed in amounts from about 0.25 to 2% and the hydroxy ester in amounts from about 0.1 to 2% by weight on the finished oil. In other cases, as where concentrates or greases are desired, or where the hydroxy ester constitutes the effective lubricant, much larger quantities of metal carboxylate or hydroxy ester or both will be used, for example from 10% to 50% each of metal carboxylate and hydroxy ester.

The additives of this invention may be employed in various types of oil, such as the more viscous petroleum distillates, petroleum residua, viscous olefin polymers, lubricating oils produced from oxides of carbon or other forms of carbon by hydrogenation, etc., the newer synthetic lubricants such as amyl naphthalene and butyl phthalate, solvent refined petroleum oils, acid refined petroleum oils, aluminum chloride refined petroleum oils, greases, transformer, switch and cable oils, and the like.

In the first two examples below are set forth data showing the comprehensiveness of our discovery that polar substituents greatly modify and improve the performance of metal alkyl carboxylates. In the third example are set forth data showing how the performance of polar substituted metal alkyl carboxylates is modified and improved by the employment therewith of esters of hydroxy substituted aliphatic carboxylic acids.

EXAMPLE I

Ring sticking and engine cleanliness

In the tests whose results are summarized in Table I below, a single cylinder Lauson gasoline spark-ignition engine, 2 1/8 inch bore and 2 1/2 inch stroke, loaded with fan dynamometers, was operated under extremely severe conditions, designed to develop fully the tendency of the crankcase lubricant to deteriorate with gum formation and piston ring sticking: operation was at 1600 R. P. M.; engine jacket temperature was maintained at 375° F.; crankcase oil temperature was maintained at 220° F.; at periods of 15 hours the operations were interrupted and the condition of the piston rings determined. In Table I, the base oil referred to as "Western SAE 30" was an acid-refined lube stock of California origin; A. P. I. gravity 21.4°; viscosities at 100° and 210° of 622 seconds and 56.6 seconds, respectively, Saybolt Universal. To this base oil were added the various salts in the amounts indicated, by weight. The base or uncompounded oil referred to as "Pennsylvania SAE 30" was a solvent refined stock of Pennsylvania origin, A. P. I. gravity 28.6°; viscosities at 100° and 210° F. of 519 and 66 seconds, respectively, Saybolt Universal.

Table I

Oil	Additive	Hours to cause ring sticking	Relative cleanliness of—	
			Ring slot	Piston
Western SAE 30.	Nil.	30	Poor.	Poor.
Do.	0.28% K cetyl tartrate.	60+	Good.	Good.

Do.	0.52% Al cetyl citrate.	60+	Good.	Fair.
Do.	0.50% Ca alpha-cetylmalonate.	75	Fair.	Poor.
Do.	0.50% Ca alpha,cetylsuccinate.	90	Fair.	Do.
Do.	0.40% Ca cetyl alpha-aminosuccinate.	60+	Very good.	Very good.
Pennsylvania SAE 30.	Nil.	30	Poor.	Poor.
Do.	0.50% Ca cetyl tartrate.	60+	Good.	Do.
Do.	0.63% Ca alpha-hydroxy stearate.	60+	Fair.	Fair.

EXAMPLE II

Bearing alloy corrosion

In the tests whose results are summarized in Table II, thin sheets of the indicated bearing metals were cut into strips (copper-lead, 1/8" x 1 1/4" x 3/2"; cadmium-silver 1/2" x 1 1/8" x 1/8"), and these strips were immersed in the exemplified oils carried in 2" x 20" glass test tubes; these test tubes were carried in an oil bath maintained at 300° F. ±1° F., except where indicated as 325° F. Each test tube contained approximately 300 cc. of oil, and air was bubbled through each tube at the rate of 10 liters per hour. At the end of each of three 24-hour periods, the strips were removed from the oils, washed with petroleum ether and carefully wiped with a soft cotton cloth; weight losses of the strips were measured in connection with the weight of each individual strip. The duration of the tests was 72 hours, and the weight losses tabulated below are those found at the end of the 72 hour period.

Attention is directed to the fact that in Table II are shown corrosion results with (1) base oil, (2) base oil plus prior art additives (fatty acid, naphthenic acid and phenolic salts) and (3) base oil plus polar substituted metal alkyl carboxylates of the invention. Except for White oil No. 15 (39.0 mgms. corrosion loss with Cu-Pb) the base oil in every case exhibited very low corrosivity. Each base oil when compounded with a metal salt of an unsubstituted fatty acid (with the exception noted below) exhibited greatly increased corrosion of both Cu-Pb and Cd-Ag strips. The metal naphthenates likewise caused considerable corrosion of both types of bearing metal, though substantially less corrosion of Cd-Ag than caused by Ca stearate. Calcium cetyl phenate caused very little corrosion of the Cd-Ag strip in Western SAE 30 but caused considerable corrosion of the Cu-Pb strip. In increasing order of merit, therefore, the prior art additives rank as follows: metal salts of unsubstituted fatty acids < metal naphthenates < metal phenates. In every case, however, the polar substituted metal alkyl carboxylates of the invention exhibited greatly reduced corrosion compared to the above-mentioned prior art additives, great reduction in corrosion was exhibited with both Cu-Pb and Cd-Ag, and in nearly all cases the compounded oil was less corrosive than the base oil.

It will be noted that calcium acetate exhibited low corrosivity, even less than the base oil. However, as shown by Ca silicato-tetra-acetate, Ba thiosulfatoacetate, Ca glycolate and Ca cyanacetate, the polar substituted acetates are even less corrosive than Ca acetate.

¹ Note: Tests carried out at 325° F.

Besides detergency (inhibition of ring sticking and maintenance of piston cleanliness) and corrosion inhibition, shown by Tables I and II above, the polar substituted metal alkyl carboxylates of the invention in many cases exhibit other valuable properties when added to hydrocarbon oils, such as color stabilization, inhibition of oxidation, reduction of wear, and improvement of film

strength. With the large number of salts available, it is possible to choose a salt which is best for a particular use upon taking into consideration factors such as the nature of the base oil, the nature of other compounding agents, and the conditions of use of the compounded oil. The salts of the invention are not equally effective in every respect. Some have particularly marked detergent properties, others have particularly marked corrosion or oxidation inhibiting properties, etc. The metal of the salt, the polar substituent and its position, the nature of the carboxy acid, and the amount in which the salt is used all have an influence upon the final result.

EXAMPLE III Combination effect

An SAE 30 blend of refined paraffinic and naphthenic oils was used as the base oil. This base oil, blends of base oil with metal salts of polar substituted alkyl carboxylic acids, and blends of base oil with said metal salts and esters of hydroxy carboxylic acids, were submitted to strip corrosion tests as follows:

300° F. corrosion test.—A clean strip of copper-lead bearing metal approximately $\frac{1}{8}$ " wide by 2" long is weighed to the nearest 0.1 milligram. Approximately 10 grams of steel wool and a copper strip are placed in a 2" x 16" test tube and 300 cc. of the oil to be tested are introduced into the tube. The tube is placed in a bath maintained at 300° F. ± 2 ° F. The weighed strip of bearing metal is suspended from a hook on a rod about 3" from the bottom of the rod and the rod is placed in the test tube so that it rests on the steel wool. Air is blown through the oil in the tube at the rate of 30 $\pm$ 5 liters per hour. The strip is removed at 24 hour intervals, carefully cleaned of oil and weighed and is then replaced in the oil.

325° F. corrosion test.—Substantially the same technique is employed as in the 300° F. test, the only differences being as follows: The temperature of the bath is maintained at 325° F. ± 2 ° F.; 400 cc. of oil are used; air is passed through at the rate of 10 $\pm$ 1.5 liters per hour; the steel wool is omitted and the rod rests upon the bottom of the tube.

In these tests the steel wool and copper strip catalyze oxidation of the oil; hence, promote formation of corrosive substances.

The results of the corrosion tests are set forth in Table III below, along with used oil inspections:

The isoamyl tartrate and butyl citrate referred to in Table III were the neutral esters. The calcium "viscous oil" succinate of Table III was a salt prepared by condensing viscous oil butene polymers (about C_{20} to C_{30}) with maleic anhydride and forming the normal calcium salt. It was, therefore, the calcium salt of a mixture of alkenyl succinic acids.

The preparations of many of the metal salts of polar substituted alkyl carboxylic acids referred to above are illustrated in the aforesaid copending applications Serial Nos. 322,946; 350,054 and 350,055. Methods of preparing esters of hydroxy substituted aliphatic carboxylic acids are well known. Methods suitable for compounding these additives with hydrocarbon oils are given in said copending applications, and other methods will be apparent. The structural formulae and preparative methods for certain of the polar substituted metal alkyl carboxylates which are not described in said copending applications are described below.

with nitric acid and then with fuming nitric acid. Excess nitric acid is removed on a water bath and the resulting impure beta-phosphonatoisobutyric acid is dissolved in water and barium hydroxide is added until the solution is strongly alkaline. It is then heated to boiling and filtered and the filtrate is discarded and the desired barium salt is recovered from the residue by extraction with cold water. The extract is evaporated to dryness and pure barium beta-phosphonatoisobutyrate is recovered as the residue.

Calcium gamma-oximinovaleate.—25 grams of levulinic acid are dissolved in 250 cc. of water and 15 grams of hydroxylamine hydrochloride are added to this solution. The solution is made slightly alkaline with NaOH and is allowed to stand over night. It is then acidified with H_2SO_4 and extracted with ethyl ether. The ether is evaporated and the residue of acid is dissolved in water and neutralized with calcium hydroxide. The solution of calcium salt is evaporated to dryness.

Barium thiosulfatoacetate.—19 grams of chloroacetic acid are dissolved in 100 cc. of water and neutralized with a saturated solution of 10.6 grams of Na_2CO_3 . 50.3 grams of sodium thiosulfate pentahydrate are added to the solution and the solution is evaporated to $\frac{1}{2}$ its original volume. The barium salt is precipitated by the addition of $BaCl_2$ and it is recovered by filtration and is dried.

Calcium alpha-thiocyanatopropionate.—20 grams of ethyl alpha bromopropionate are mixed with an alcoholic solution of 10.7 grams of KSCN. The solution is allowed to stand several days on a steam plate, and potassium bromide is then filtered off. Excess calcium hydroxide solution is then added and the mixture is heated. CO_2 is passed through the mixture to remove excess lime and the calcium carbonate is removed by filtration. The filtrate is evaporated to dryness.

Barium succinamate.—19.8 grams of succinimide are dissolved in water and a solution of 31.6 grams of barium hydroxide octahydrate is added. The solution is evaporated to dryness.

Calcium alpha-nitratopropionate.—20 grams of zinc lactate are added to a mixture of 25 grams of fuming nitric acid and 40 grams of concentrated sulfuric acid. The mixed acid is kept below 40° F. while adding the zinc lactate. The solution is allowed to warm and most of the excess nitric acid is removed on a hot water bath. The residue is poured into a large amount of cold water from which a heavy oil separates. This is neutralized with calcium hydroxide solution and the water is removed on a steam plate.

Calcium levulinate.—20 grams of levulinic acid are dissolved in 500 cc. of water and the solution is neutralized with a lime slurry. It is then heated on a steam plate, filtered and evaporated to dryness.

Calcium alpha-aminocaprylate.—15 grams of alpha-aminocaprylic acid are mixed with sufficient ethyl alcohol to make a thin paste and this paste is added slowly to 500 cc. of water while stirring. A 20% KOH solution is added until solution just occurs. A solution of 5.25 grams of $CaCl_2$ in a small amount of water is added while stirring. A curdy precipitate forms which is filtered off and dried in a desiccator.

Calcium alpha-hydroxaminobutyrate.—14.2 grams of sodium are dissolved in 200 cc. of absolute alcohol and to the solution is added a solution of 43 grams of hydroxylamine hydrochloride in 200 cc. of absolute alcohol. 21.5 grams of crotonic acid dissolved in 100 cc. of alcohol are added to the above solution and the mixture is allowed to stand 3 days at room temperature.

5 Alcohol is then evaporated off, leaving a thick, viscous residue. This is extracted with hot alcohol. The alcoholic extract is neutralized with lime slurry and the solution of calcium salt is evaporated to dryness.

10 *Calcium beta-nitropropionate.*—15.3 grams of beta-iodopropionic acid are dissolved in 400 cc. of water and the solution is cooled to 40° F. 12.23 grams of silver nitrite are added slowly to the solution and the mixture is allowed to warm to room temperature. The solution is filtered to remove silver iodide and evaporated under vacuum to a volume of about 100 cc. Excess calcium hydroxide is added and the excess is removed by treating with CO_2 and filtering off calcium carbonate. The filtered solution is evaporated to dryness.

15 *Calcium cystinate.*—12 grams of cystine and 3.7 grams of calcium hydroxide are added to 500 cc. of water. The mixture is heated on a steam plate for $\frac{1}{2}$ hour and filtered. The residue on the filter is leached several times with hot water and the filtrate is evaporated to dryness, leaving a brown colored residue.

20 *Calcium glycolate.*—An aqueous solution of 30 glycolic acid is neutralized with calcium hydroxide and the solution of calcium glycolate is filtered and evaporated to dryness.

25 *Calcium cyanoacetate.*—20.5 grams of cyanoacetic acid are dissolved in 500 cc. of water and 35 the solution is neutralized with lime slurry. The solution is heated on a steam plate, filtered and evaporated to dryness.

30 *Calcium beta-phosphatopropionate.*—13.6 grams of beta-iodopropionic acid are dissolved in 40 200 cc. of water and 9.5 grams of silver phosphate are added. The mixture is heated $\frac{1}{2}$ hour and the silver iodide is filtered off. Calcium hydroxide is added until the solution is neutral, and the solution is then evaporated to dryness.

35 We claim:

1. A composition of matter, comprising a major proportion of hydrocarbon oil and a small amount each not less than about .1% by weight based on finished oil of a metal salt of an alkyl carboxylic acid and an ester of an hydroxy substituted aliphatic carboxylic acid, said metal salt of an alkyl carboxylic acid having a polar substituent attached to an aliphatic carbon atom near enough to a metal alkyl carboxylate group to reduce substantially the corrosive tendency of said metal salt in the absence of said polar substituent toward bearing alloys of the type represented by copper-lead and cadmium-silver bearing alloys.

40 2. A lubricant comprising a small amount each not less than about .1% by weight based on finished lubricant of a polyvalent metal salt of an alkyl carboxylic acid and an ester of an hydroxy substituted aliphatic carboxylic acid, said metal salt of an alkyl carboxylic acid having a polar substituent attached to an aliphatic carbon atom near enough to a metal alkyl carboxylate group to reduce substantially the corrosive tendency of said metal salt in the absence of said polar substituent toward bearing alloys of the type represented by copper-lead and cadmium-silver bearing alloys.

45 3. A composition of matter, comprising a major proportion of hydrocarbon oil, about 0.1 to 2% by weight based on finished oil of a polyvalent

metal salt of an alkyl carboxylic acid and about 0.25 to 2% by weight based on finished oil of an ester of a lower molecular weight hydroxy substituted aliphatic carboxylic acid, said metal salt of an alkyl carboxylic acid having a polar substituent attached to an aliphatic carbon atom near enough to a metal alkyl carboxylate group to reduce substantially the corrosive tendency of said metal salt in the absence of said polar substituent toward bearing alloys of the type represented by copper-lead and cadmium-silver bearing alloys.

4. A composition of matter, comprising a major proportion of mineral oil of lubricating viscosity, about 0.1 to 2% by weight based on finished oil of a polyvalent metal salt of an alkyl carboxylic acid and about 0.25 to 2% by weight based on finished oil of an ester of a lower molecular weight hydroxy substituted aliphatic carboxylic acid, said metal salt of an alkyl carboxylic acid having a polar substituent attached to an aliphatic carbon atom near enough to a metal alkyl carboxylate group to reduce substantially the corrosive tendency of said metal salt in the absence of said polar substituent toward bearing alloys of the type represented by copper-lead and cadmium-silver bearing alloys.

5. The composition of claim 4, wherein said polar substituent is in the alpha, beta or gamma position with regard to a metal alkyl carboxylate group.

6. The composition of claim 4, wherein said metal salt is the salt of a polyvalent metal and a polycarboxylic aliphatic acid containing at least two alkyl carboxyl groups separated by not more than three aliphatic carbon atoms.

7. The composition of claim 4, wherein said metal salt is the salt of a polyvalent metal and an alpha, beta or gamma hydroxy substituted aliphatic acid.

8. The composition of claim 4, wherein said metal salt is the salt of a polyvalent metal and an aliphatic carboxylic acid substituted in an alpha, beta or gamma position with regard to a metal alkyl carboxylate group by a substituent containing an element selected from the group consisting of oxygen, sulfur, selenium, nitrogen and phosphorus.

9. The composition of claim 4, wherein said metal salt is the salt of a polyvalent metal and an alpha, beta or gamma sulfur substituted alkyl carboxylic acid.

10. A compounded mineral lubricating oil, comprising about 0.1 to 2% by weight based on finished oil of a polyvalent metal salt of an alpha, beta or gamma polar substituted aliphatic carboxylic acid, and about 0.25 to 2% by weight based on finished oil of an ester of an aliphatic alcohol of 1 to 6 carbon atoms and an alpha, beta or gamma hydroxy substituted aliphatic carboxylic acid of 2 to 6 carbon atoms.

11. The compounded oil of claim 10, wherein said ester is the ester of an hydroxy substituted fatty acid.

12. The compounded oil of claim 10, wherein said ester is the ester of an hydroxy substituted aliphatic polycarboxylic acid.

13. A compounded mineral lubricating oil, comprising about 0.1 to 10 per cent by weight based on the finished oil of a polyvalent metal salt of an alpha, beta or gamma polar substituted aliphatic carboxylic acid and about 0.1 to 10 percent by weight based on the finished oil of an ester of a C₁ to C₆ aliphatic alcohol and a C₂ to C₆ hydroxy substituted aliphatic carboxylic acid containing at least one hydroxyl substituent in an alpha position with respect to a carboxyl group.

14. The compounded oil of claim 10, wherein said ester is isoamyl tartrate.

15. The compounded oil of claim 10, wherein said ester is butyl citrate.

16. A compounded mineral lubricating oil, comprising about 0.1 to 2% by weight based on finished oil of an oil soluble polyvalent metal salt of an aliphatic polycarboxylic acid and about 0.25 to 2% by weight based on finished oil of a low molecular weight alkyl ester of an hydroxy substituted aliphatic polycarboxylic acid.

17. A concentrated solution in mineral oil of lubricating viscosity of a metal salt of an alkyl carboxylic acid and an ester of a lower molecular weight hydroxy substituted aliphatic carboxylic acid, said metal salt of an alkyl carboxylic acid having a polar substituent attached to an aliphatic carbon atom near enough to a metal alkyl carboxylate group to reduce substantially the corrosive tendency of said metal salt in the absence of said polar substituent toward bearing alloys of the type represented by copper-lead and cadmium-silver bearing alloys.

18. A grease, comprising soap, mineral oil, and an ester of an hydroxy substituted aliphatic carboxylic acid, at least part of the soap being a metal alkyl carboxylate having a polar substituent attached to an aliphatic carbon atom near enough to a metal alkyl carboxylate group to reduce substantially the corrosivity of said metal alkyl carboxylate in the absence of said polar substituent toward bearing alloys of the type represented by copper-lead and cadmium-silver bearing alloys.

19. The oil of claim 13, wherein said aliphatic carboxylic acid is tartaric acid.

20. The oil of claim 13, wherein said aliphatic carboxylic acid is citric acid.

21. The oil of claim 13, wherein said aliphatic carboxylic acid is malic acid.

BRUCE B. FARRINGTON.
JAMES O. CLAYTON.
